CHAUNCEY A. CORNELL, OF DETROIT, MICHIGAN

TURRET MACHINE FOR METAL WORKING

Application filed September 11, 1925. Serial No. 55,858.

The invention relates to metal working and has among its objects to provide an improved method and apparatus for machining drop forgings, castings, etc.

5 A further feature of the invention resides in providing a plurality of machines simultaneously operable under a common control for performing various operations on the work as the latter is moved successively 10 from machine to machine. Thus, I have provided a work carrier in the form of a rotatable table upon which is mounted a plurality of jaws for clamping the work. This table is fitted with an indexing and rotating apparatus whereby the table is given successive 15 movements for a predetermined arc to successively move the work to the various machines arranged adjacent and around the periphery of the table. Thus, at each of the 20 points of indexing the machines are caused to operate on the work, each machine performing one of a series of operations which go to make up a complete job.

A further feature of my invention resides 25 in the control means for rendering the operations of the machines automatic, each machine performing its operation and coming to rest awaiting the next indexing of the table.

30 Another object resides in the provision of a lubricating system for supplying lubricant to the machines and work.

With these and other objects in view, the invention resides in the novel features of 35 construction and combination and arrangements of parts as more fully hereinafter described and claimed.

40 Referring to the drawings in which like reference characters indicate corresponding parts,

Figure 1 is a plan view illustrating an arrangement of the machines and work carrying table;

45 Figure 2 is a sectional elevation view along 2-2 of Figure 1;

Figure 3 is a plan view of the table support;

50 Figure 4 is an elevation view thereof; Figure 5 is a fragmentary elevation view

illustrating in detail the locking means for the table indexing mechanism;

Figure 6 is an elevation view showing the means for indexing the table from station to station;

55 Figure 7 is a view in elevation illustrating a typical machine for performing one of the series of operations on the work;

Figure 8 is a plan view of this machine;

Figure 9 is a detail view along 9-9 of Figure 8;

60 Figure 10 is a detail view in elevation illustrating one form of connection between the horizontally sliding table and the operating arm therefore;

65 Figure 11 is a fragmentary sectional view in elevation illustrating another of the series of operations upon the work;

70 Figures 12 to 22 inclusive illustrate the successive operations performed by the machines on a connecting rod;

75 Figure 21^a being a side elevation view of the lower part of the connecting rod shown in Figure 21;

Figure 23 is a transverse view through another of the machines illustrating another type of machine;

Figure 24 is an elevation view of the air and lubricant supply tanks;

80 Figure 25 is a plan view of the foundation member or supporting base for the machines; and

Figure 26 is a sectional view in elevation along 26-26 of Figure 25.

85 In the drawings, reference character A represents the table supporting base provided with the supporting legs 10 and preferably cast for convenience in shipping and handling in three sections which, when assembled, are bolted together as shown at 11.

90 The base A is further provided with a V-groove 12 which extends circumferentially around the base. At a plurality of points, preferably three, as shown in Figure 3, I have provided the pockets 13 for receiving the bearing supporting members 14 which mount the roller bearings 15, the latter being provided with a V-groove for supporting engagement with the table as will be presently apparent. The members 14 are vertically ad-

55

justable in the pockets 13 and for positioning these members at the desired height I have provided the adjustment bolts 16 and the lock nuts 17.

5 B represents the work carrier or rotatable table which is preferably ring-shaped as shown in Figure 1, this table preferably being cast in four sections whereby the joints 18 will lie intermediate the joints 11 of the base A so as not to break even with these joints of the base. The table is provided with a downwardly extending V-projection 19 for engagement in the V-slot 12 of the base A. The projection 19 further engages the bearings 15 and by adjusting these bearings to the proper height the weight of the table may be relieved from the base and largely placed on the bearings 15 to relieve to a large extent the friction between the projection 19 and the groove 12. For further facilitating the movement of the table, the pockets 13 may be filled with a suitable lubricant so that as the rollers 15 revolve the lubricant will be carried to the V-projection 19 whereby the lubricant will be distributed around the groove 12. The table B is further provided with a circumferential recess 20 for receiving at the desired circumferentially spaced points the indexing sections 21. The number of 10 these indexing sections will correspond with the number of stations desired to perform the successive operations on the work as will be presently apparent. The sections 21 are provided with the wedge-shaped grooves 22, 15 the side walls of the grooves being also tapered inwardly and downwardly toward each other as shown at 23. Referring to Figure 5 I have shown in detail the locking means engageable successively with the indexing members for holding the table relatively stationary while the various machines or 20 machine units are performing their operations on the work. 24 represents a locking member which is arcuate and which is provided with a wedge-shaped outer portion 25, the side walls of which taper outwardly and upwardly for wedging engagement with the tapered walls 23 of the recessed portions 22. The locking member 24 is pivotally mounted at 25 26 in a support 27, the member 24 being rotated about the pivot through an arm 28 actuatable by a rod 29. The rod 29 is moved by a piston 30 controlled by means described hereinafter. The piston 30 is operable with- 30 in the cylinder 31, the latter being pivoted at 32 to the base 33 of the support 27. Any suitable fluid under pressure, such as air may be used to move the piston 30 in its opposite directions to cause the locking member 24 to 35 engage the recesses 22 or to be disengaged therefrom.

For moving the table a predetermined amount determined by the spacing of the indexing points, I have provided a bar 34 which 40 may be mounted in a downwardly opening

recess of the table as shown in Figures 2 and 6. This bar is provided with the spaced lugs 35 having the abrupt shoulders 36 at one side thereof and the inclined sides 37 at the opposite side. For engaging the sides 36 of these lugs to impart a step by step indexing movement to the table I have provided a carriage C comprising a rear section 38 and a forward section 39. These sections are mounted on rollers 40 rotatably guided on the track 41. 42 represents the meeting edges of the sections 38 and 39 and at this point groove 43 is provided to permit relative movement of the carriage sections. These sections are further linked together by a link member 44 pivoted at 45 and 46 with the sections 38 and 39 respectively. The rear section 38 is provided with a fork 47 between which is guided an operating bar 48 of the forward section 49. This latter bar as shown in Figure 6, is preferably curved upwardly for engagement with the lugs 35. For reciprocating the carriage C to impart the step by step movement to the table B I have provided a cylinder 49 pivoted at 50 to a suitable support and having 55 therein a suitable piston for operating a piston rod 51 connected at 52 to a radial bar 53. This bar is pivotally mounted at 54, this point preferably corresponding to the center of the ring-shaped table B. The opposite end of the bar 53 is connected to the forward section 39 of the carriage C for reciprocating the same.

Describing the operation of the indexing mechanism for imparting a step by step movement to the table B, a suitable fluid such as compressed air is introduced to the cylinder 49 for operation upon the piston within the same, the controlling means for this fluid being described hereinafter. Movement of the piston within the cylinder 49 actuates the rod 51 to move the bar 53 about its pivotal point 54. With the parts as shown in Figure 9, the table B is ready to receive a cycle of the carriage mechanism for moving the same to the next indexing point. The operator first causes disengagement of the locking member 24 from its indexing section 22 and thereafter the fluid is introduced to the cylinder 49 for moving the carriage C to the left as shown in Figure 9. The stroke of the piston rod 51 is such that the carriage C will be moved a distance corresponding to the spacing of the lugs 35 whereby the operating bar 48 will engage the inclined face 37 of the next adjacent lug. As the operating bar slides along this inclined face the bar will be swung about a fulcrum point which will be its supporting roller 40. Thus, a buckling movement of the section 38 and 39 110 is brought about, the notch 43 and link 44 permitting such a movement. The fork 47 serves to guide the operating bar 48 and maintain the same in proper position during this buckling movement. After the upper 115

extremity of the bar 48 has passed beyond the incline 37 the weight of the carriage sections and cause them to return to their normal positions, with the upper shouldered face 54 of the bar 48 against the shoulder 36 of the lug. In this position fluid is introduced to the opposite end of the cylinder 49 for causing a movement of the carriage C to the right as shown in Figure 9, whereby the table B 10 will be moved through an arc corresponding to the spacing of the lugs 35 and the spacing of the indexing sections 21.

With the mechanism as thus far described, it will be noted that I have provided a work 15 carrying table which is adapted to be successively moved throughout predetermined distances with means for locking or holding the table in its successive points of indexing. Before describing in detail the various 20 machines for operating on the work which is carried by the table, I will briefly outline in a general way the operation of the system. For purpose of illustration, I have shown in the drawings 12 indexing points for the table 25 B. Thus, in a complete rotation of the table, the latter will be successively stopped and indexed twelve times. I have, therefore, provided twelve stations or indexing points D and at each of these stations I may provide 30 one or more machine units for performing the successive operations on the work. Thus, E¹ represents the machine unit positioned adjacent the outer periphery of the table B, this machine being adapted to perform the 35 first of the series of operations upon the work carried by the table. As will be later apparent, each machine may be provided with a twin head or twin mechanism whereby two pieces of work may be simultaneously operated 40 upon the same machine. If desired and as shown in Figure 1, I may provide a second series of machine units arranged at each of the stations D around the inner periphery of the ring-shaped table B. Thus, F¹ represents 45 the first machine of this inner series for performing on the work the first step of a series of operations outlined for performance by this series of machine units. Likewise, E² represents the second machine 50 of the outer series of machines which is positioned at the second of the stations D. F² is the machine at this same station, this machine being the second of the inner series. I have continued these series of machines 55 around the table B at the various stations or indexing points whereby the outer series of machines E¹ to E¹¹ inclusive are provided. Corresponding to each of these machines is a machine of the inner series, these latter 60 machines being represented at F¹ to F¹¹ inclusive. The twelfth station D' may be left free of machine units so that at this point the operator can remove the completely machined articles of work which have been successively operated upon by the various ma-

chines of the two series and also to place on the work table new forgings or castings for a like series of operations. It will be readily understood that the number of stations or indexing points may be diminished or increased from those shown and where the work is of such a character as not to require the large number of stations which I have illustrated, additional loading and unloading stations corresponding to the station D' may be provided throughout the movement of the work table.

I have provided a plurality of machine units which are provided with suitable heads for performing all of the usual and necessary operations of a machine shop for completely machining drop forgings, castings, etc. Thus as will be presently apparent I have provided means for milling, drilling, counterboring, countersinking, boring, tapping, sawing, reaming, grinding, etc., either vertically or horizontally, or at other angles with single or multiple spindles as required. My invention is in no way limited to the machining operations for any article in particular, but is adapted to perform successive machining operations on various cast or forged articles and will be found especially useful where a large number of machining operations are required. For purpose of illustration, I have shown the machines of my system as being adapted to machine the usual drop forge or cast connecting rods commonly used in the present day motor vehicle internal combustion engine. Before describing the machine units whereby the various machining operations aforesaid may be accomplished, I will point out the various successive machining operations which may take place at the eleven stations or indexing points which I have illustrated in Figure 1.

Referring to Figure 12, 55 represents a drop forge or cast connecting rod as it comes from the forge or mold. These connecting rods are placed on the work table B at the loading and unloading station D' after the previously machined connecting rods have been removed by the operator at this station. After the various machines have completed their operations the table B is moved the distance of one of the stations and tracing the path of the connecting rods placed on the table at the station D', these rods will be moved to the first operating station comprising the machines E' and F'. At this station the machine E' drills the holes 56 for later receiving the usual cap bolts as shown in Figure 13. While the machine E' is drilling the holes 56 the machine F' drills the hole 57. After these machines have completed their respective operations they are automatically returned to the inoperative position by mechanism hereinafter described and when all of the machines have completed their respective operations the table is again indexed and an

additional forged or cast connecting rod will be moved to the first station for receiving the same operation by the machines E' and F'. Likewise, the connecting rods formerly 5 at this station will be moved to the next station for operation by the machines E² and F² to machine the connecting rods as shown in Figure 14. Thus, at this station the machine E² will rough bore the hole 56 as shown at 58. 10 While this machining operation is taking place the machine unit F² will drill the hole 59 in the opposite end of the connecting rod for later tapping. The next series of operations is illustrated in Figure 15, the machine E³ 15 finishes boring the hole 56 as illustrated at 60, while the machine F³ drills the hole 61.

At the next station as shown in Figure 16, the machine E⁴ will spot face the top side of one end of the connecting rod at 62 while the 20 machine F⁴ will ream the hole 63. At the next station illustrated in Figure 17 the machine E⁵ will spot face the bottom side 64 while the machine F⁵ mills the top and bottom cheek of the other end of the connecting rod at 65. In the next operation as illustrated in Figure 18 the machine E⁶ will mill the faces 66 for later receiving bolt heads while the machine F⁶ countersinks the hole 59 as shown at 67. At the next station the machine E⁷ 25 will ream the bolt holes as at 68, while the machine F⁷ saws a slot 69.

Figure 20 illustrates the operations at the next station at which the machine E⁸ will spot face the surface 70 for later receiving 30 the bolt ends while the machine F⁸ taps the hole at 71. At the next station as shown in Figure 21, the machine E⁹ mills the bottom of the connecting rod at 72 for forming an oil splashing surface while the machine F⁹ is 35 idle. In machining certain articles where the machines are arranged on opposite sides of the path of the article as shown in Figure 1, the machines on one side may finish their operations before those on the other side so that 40 one or more of the machines may be idle while those on the other side are completing their operations. I prefer to locate machines at these idle points, however, since when the system is used in connection with other pieces of 45 work, these machines may then be readily brought into operation to perform one of the machining steps. In Figure 21^a I have illustrated the character of the milled bottom 72 which is in the nature of an arch-shaped 50 surface for splashing the oil contained in the usual crank case. To form this surface 72 I prefer for convenience, to provide two successive operations. Thus, the machine E⁹ may mill the bottom 72 by a substantially horizontal 55 movement of the milling cutter while the machine E¹⁰ at the next station will be provided with a radial milling cutter to produce the arch-shaped surface as shown in Figure 21^a.

60 At the last machine station, as shown in

Figure 22, the machine E¹¹ will form the saw slot 73 whereby the cap 74 will be removed from the connecting rod whereupon the machines F¹⁰ and F¹¹ are idle. The next point of indexing is the station D' where the finished connecting rod will be removed from the table and the new raw stock substituted. 70

I will now describe a typical machine whereby the various operations at the different stations as outlined above may be accomplished. Referring to Figures 7 and 8 I have shown such a machine in which 75 is the base journalling the cam driving shaft 76 by reason of the bearings 77 and 78. Fixed to this shaft is a gear 79 adapted to be driven by a pinion 80, the latter gear being driven from a shaft 81 through the shaft friction coupling clutch 82. 83 is a motor for driving the shaft 81 through the reduction gearing 84. The clutch 82 and hence the driving connection between shaft 81 and shaft 76 is controlled by a yoke 85 movable with a bell crank lever 86 pivoted at 87 with the depending supporting lug 88. 89 is the other arm of the bell crank 86 and this arm is adapted to be actuated by a clutch cam 90 fixed to the shaft 76. 91 is a spring for returning the bell crank lever to the lower position as shown in Figure 7 after the high point of the cam 90 has passed the point of contact with the arm 89. 92 represents an electro-magnet adapted to hold the arm 89 in its upper position under the control of the operator as will later be apparent. The arm 89 in its uppermost position is adapted to contact with the core 93 of the electro-magnet. 94 is a member adapted to bridge the switch points 95 so as to form a circuit in the leads 96 and 97 when the arm 89 is in its raised position for flashing a signal light to advise the operator that the machine has completed its operation. The majority of operations upon the work 55 may be accomplished by moving the tool of any machine either vertically, horizontally, or a combination of these two movements. In order to provide for movements of the tool of this nature, I have incorporated in each machine a tool head which is capable of both vertical and horizontal sliding movement. Thus, in the typical machine illustrated in Figure 7, 98 is a sliding head capable of sliding movement toward and from the table, this head being mounted for this purpose to slide in the grooves 99. 100 represents the head support which is vertically 110 slidable in the groove 101 whereby the parts carried by the sliding head 98 will be raised vertically, the sliding head separating from the base 75 along the line 102. For limiting the lower position of the head support 100 I have provided a stop 103 threadedly adjustable in the base 104 and engageable with the lug 105, the latter being fixed with the head support 100. For imparting a vertical 115 movement to the head support 100 and the 120

75

80

85

90

95

100

105

110

115

120

125

130

sliding head 98 I have provided a cam 106 removably secured to the shaft 76. In Figure 7 this cam is shown in dotted lines as in the particular operation illustrated in this figure, this cam will not be used as it is not necessary to vertically move the tool. In other operations, however, and as hereinafter pointed out in connection with Figure 11, it is desirable to provide for such vertical movement and in such instances the cam 106 is engageable with a lift rod 107 slideable in the bearings 108 and 109 to raise the head 98, the latter being guided in such movement by the sliding of the head support 100 in the slide or groove 101.

For imparting a sliding movement to the head 98 whereby the tool may be moved toward or from the work I have provided a cylinder cam 110 having a cam groove 111 within which operates the roller 112 carried by the operating arm 113. The typical operating arm is pivotally mounted at 114 to the base of the machine and as shown in Figure 7 terminates in an arcuate slotted portion 115 slidably receiving a block 116 which is fixed with the sliding head 98. Adjustable screws 117 are preferably threaded in the arm 113 at the opposite ends of the slot and are adapted to abut the block 116 in the opposite movements of the arm 113 for driving the sliding head from the arm. It will thus be noted that I have provided a lost motion, the amount of which may be adjusted by the screws 117, the latter being locked in any adjusted position by reason of the lock nuts 118. The purpose of this lost motion is to provide various movements of the sliding head 98 from the same type of cam 110. Thus where the operation to be performed by any machine varies slightly from the operation previously used in connection with the machine, the same cam 110 may be used and the difference in movement desired for the head 98 may be taken care of by the adjusting screws 117. In Figure 7, I have not shown this typical form of operating arm 113 as the operation shown in Figure 17 is such that it is not desirable to provide a sliding movement of the head 98. In this figure, the arm 113 is reciprocated freely in a guide 119 and the upper extremity of the operating arm 113 is bent at 120 to extend across the sliding head 98 terminating in a yoke 121. 122 is a fulcrum point for the portion 120 of the operating arm 113.

In Figures 7 and 8 I have shown for purpose of illustration the operation described in Figure 13 in connection with the machine E' for drilling the holes 56. Figure 8 also illustrates one manner in which the connecting rods 57 are clamped in pairs upon the table B, it being understood that a similar pair of clamping devices are provided at each of the indexing points throughout the circumference of the table B. In this figure,

each of the work clamps or vises G is formed of the complementary parts 123 and 124, the former being fixed with respect to the table B and the latter being slideable in the slide 125 toward and away from the part 123 to clamp or release the connecting rod 57. In order to clamp the work between the parts 123 and 124 I have provided a toggle lever arrangement comprising the toggle levers 126 and 127, these levers being pivoted at 128 to their respective clamp parts 124. The opposite ends of the toggle levers are hinged at 129 about the pintle 130 which is upstanding from a slide 131 adapted to be guided in the side grooves 132. 133 represents a hand wrench pivoted to the bed B at 134 and engageable with the lugs 135 and 136 of the slide whereby the latter may be moved to operate the toggle levers to release or clamp the work. For relatively adjusting the clamping parts 123 and 124 to compensate for minor variations in the castings I have formed each of the levers 126 and 127 in two parts 137 and 138, these parts being oppositely threaded and adapted to be moved toward and from each other by a collar 139. This collar may be provided with an opening 140 for accommodating a wrench or actuating bar. 141 are lock nuts for holding the parts of the toggle levers in adjusted position.

With the work clamped as shown in Figure 8 and the table properly indexed the work will be brought by the indexing mechanism into accurate alignment for operation of the various machines. As shown in Figures 7 and 8, the pair of connecting rods are positioned for drilling the holes 56, reference character 142 indicating the drills. These drills or tools are guided by the jigs 143 so that their operation will be accurately predetermined. The drills 142 are carried by the tool heads 144 which as shown in Figure 7, are slideable in the grooves 145 with respect to the sliding head 98, the latter in the particular machine illustrated being relatively stationary. 145 represents a further slide, this slide being guided in its movement in the slides or guides 146. The slide 145 is adapted to be reciprocated through a movement from the arm 120 by reason of an engagement of the yoke 121 with the pin 147. 148 is a motor carried by the slide 145, this motor being provided with a drive shaft 149, the latter being formed with the key slot 150. The shaft 149 has a bearing 151 carried by the slide 145 and is adapted to drive a bevel 152 through a sliding key 153. 154 are bevels driven from the gear 152, these bevels being mounted in bearings 155 carried by the slide 145. The bevel 152 is adapted to impart rotary movement to the drills 142 through these bevels 154. To this end the bevels 154 are adapted to drive the bevels 156 through the shaft sections 157 and 158, these sections being relatively axially 130

slidable by reason of the sliding parts 159. This sliding joint is preferably covered by a tube or sleeve 160. The bevels 156 are adapted to drive the bevels 160, the latter driving the pinions 161 by reason of the pinion 162. The pinion 162 has a bearing 163 in the tool head 144 while the pinions 161 are fixed to the shafts 164, these shafts being adapted to rotate the drills 142. 165 are thrust bearings for absorbing the thrust 10 of the drilling operation. The shafts 164 are provided with a further bearing 166. For simultaneously sliding the tool heads 144 in their slides 145 by a movement of the 15 slide 145 I have provided a casting 167 fixed with the slide 145 and to this casting is bolted and doweled at 168 and 169 respectively, a steel facing 170. The opposite ends of the facing 170 are slotted at 171 as shown in 20 Figure 9 to receive the shafts 164 and permitting a sliding movement of these shafts in the slot 171 to compensate for the relative movement of the tool heads 144 toward each other with respect to the slide 145 as these 25 slides are moved by the arm 120. Thrust bearings 173 and 172 are provided on opposite sides of the facing 170 and lock nuts 174 may be provided whereby a small amount of clearance may be afforded between the facing 170, the lock nuts 174 and the bearing 166.

Describing the operation of the machine illustrated in Figures 7 and 8, the motor 83 and the motor 148 preferably continuously 30 rotate. With the parts as shown, in these figures, the arm 89 is in its lowered position, the low point of the cam 90 being in contact with this arm whereby the clutch 82 is establishing a driving connection between the shaft 35 81 and the shaft 76. Rotation of the shaft 76 causes the cam 110 to rotate whereby the arm 113 is slowly reciprocated about its pivot 114. A complete operation of the machine is adapted to take place upon a single rotation of the 40 shaft 76, reduction gearing 84 between the rotor 83 and the gear 79 being adapted to slowly rotate the shaft 76. Movement of the arm 113 produces a swinging movement of the arm portion 129 about its pivotal portion 122, 45 whereby the slide 145 is advanced toward the table carrying with it the motor 148 and the facing 170. Movement of the facing 170 causes simultaneous forward movement of the tool heads 144 in their slides 145, thus causing 50 the drills 142 to drill the holes 56 as shown in Figure 13. Because of the angular slides 145' of the tool heads 144 with respect to the slide 145 the shaft sections 157 and 158 will move toward each other. This relative movement 55 is taken care of by the sliding connection 159. During the sliding movement of the tool heads 144 and the slide 145, the motor 148 will operate through the bevels 152, 154 and the gearing carried by the tool heads to rotate 60 the drills 142.

Upon a complete rotation of the cam 110 the drills 142 will have completely performed their operation and returned to a position sufficiently removed from the connecting rods 57 to permit rotation of the table B when the latter is indexed. Likewise, upon a complete rotation of shaft 76 the cam 90 will raise the arm 89 into engagement with the core 93 of the electro-magnet 92, whereby the arm 89 will be maintained in this raised position 70 causing disengagement of the clutch 82 and hence breaking the drive from the motor 83 to the shaft 76. The clutch 82 will be kept in its disengaged position until the operator by a control mechanism described hereinafter, 75 releases the electro-magnet 92 whereupon the spring 91 can act to again lower the arm 89. Simultaneous with the raising of the arm 89, the bridging member 94 will establish a circuit across the switch points 95 in the leads 80 96 and 97 to flash a light or other signal described hereinafter to advise the operator of the completion of the operation of the machine. 85

Referring to Figure 11, I have illustrated 90 the operation described in connection with Figure 17 and machine E⁵ for spot facing the bottom side 64 of the connecting rod. This operation involves a vertical and horizontal movement of the head 98 referred to in describing the typical machine illustrated in 95 Figure 7. In Figure 11, the connecting rod 55 is shown carried by the clamp G and in this figure I have shown the table B provided with a pair of sub-plates 175 and 176 for protecting 100 the top of the table B. These sub-plates are not entirely necessary, but are desirable in preventing marring the top of the table since with these sub-plates various bolt holes and other defacings used in connection with other various types of clamps and work fastenings will not permanently mar the table. In this figure, the sliding head 98 is shown in its forward position, this head being moved to such position by the cam 110 and the operating arm 113, the latter being connected to move the head preferably through the lost motion device shown in Figure 10. It should be understood that where the lost motion is not desired the screws 117 may be advanced sufficiently to contact with the opposite sides of 110 the driven block 116. The head 98 rotatably mounts the facing tool 177, the latter being supported through a thrust bearing 178. Rotation of the tool 177 is accomplished by a 115 worm wheel 179 and worm 180, the latter being rotated through a suitable gearing driven by a motor (not shown) corresponding to the motor 148. This motor may be mounted directly on the head 98. A recess 181 is provided in the sub-plates 175 and 176 to permit vertical movement of the tool 177 to clear the connecting rod 55 and also for feeding the tool upwardly against the work. In this 120 operation, the cam 110 first advances the head 125

98 to a position whereby the tool 177 is properly aligned beneath the end of the connecting rod. Further rotation of the shaft 76 then causes the cam 106 to raise the lift shaft 107 for raising the head support 100 and the sliding head 98 whereby the tool 177 is fed against the connecting rod to form its facing operation. During this feeding movement the tool 177 is rotated by the driving worm 180. The 10 cams 106 and 110 are suitably designed to properly feed the tool against the work and after this operation is completed the cam 110 operates to withdraw the sliding head 98 and tool 177 to clear the work and the cam 106 15 permits the downward return movement of the head support 100. The clutch 82 is then disengaged as aforesaid and the machine is ready for the next operation following an indexing movement of the table.

20 It will be apparent from the machine shown in Figure 7 that the various tools for performing the various operations may be fed in any manner desired to perform any of the operations described in connection with Figures 13 to 22 inclusive. As a further means of sliding the head 98 and also for obtaining a sliding movement of the head at various angles, I have provided a modified construction of machine, as illustrated in 25 Figure 23. In this figure the operating arm 113 is identical with that shown in Figure 7 and is adapted to drive a block 116' in a manner corresponding with the mechanism shown in Figure 10. 98' is the sliding head which may mount the necessary tools and driving motor. This head is slidable in the groove or slide 99' and is formed with a 30 rack 182 extending longitudinally beneath the top of the head. Meshing with this rack for sliding the head 98' is a pinion 183 fixed with a lift shaft 107' which may correspond in function with the shaft 107 as shown in Figure 7. The block 116' is adapted to reciprocate a rack 184 which meshes with the 35 pinion 185 rotatable about an axis 186. The pinion 185 is fixed to rotate with a gear 186', the latter meshing with a pinion 187. Fixed to rotate with this latter gear is another gear 188 adapted to drive a gear 189 having 40 splined engagement at 190 with the shaft 107' so as to drive this shaft in its various elevated positions. In this type of drive, the arm 113 is adapted to reciprocate the rack 184, the latter rotating the shaft 107' through the 45 compound reduction gearing. Rotation of the shaft 107' produces a reciprocation of the rack 182 by reason of the pinion 183 whereby the head 98' is caused to slide in the guides 99'. It will be noted that the direction 50 of sliding of the head 98' can be arranged at any desired angle with this type of drive so that movement of the tool carried by the head can be made to fall in any predetermined desired path.

55 I will now describe the controlling means

for starting the machines and indexing the work table. Referring to Figure 5, I have provided a control box 191 mounting a control handle 192 rotatable with a disc 193. This disc carries the fingers 194 and 195. 70 196 and 197 are valve controlling members adapted upon rotation to control the supply of compressed air or other fluid to the cylinders 31 and 49 respectively. Each of these controlling members is formed with a yoke 75 198 to impart a slight rotary movement to the control members as the disc 193 is rotated. 199 is a switch mechanism adapted to control the electro-magnet 92. A meter 200 is positioned to advise the operator when 80 energy is being supplied to the various electro-magnets 92 of the machine units. Gages 201 and 202 are adapted to indicate the air pressure in the opposite ends of the cylinder 31. Likewise, the gages 203 and 204 indicate the performance of the cylinder 49. Referring for the moment to Figure 24, I have shown a compressed air tank 205 adapted to store air under pressure, the supply pipe 206 being adapted to conduct the air to the cylinders 31 and 49, this supply of air being controlled by movement of the lever 192. Mounted at a convenient point, such as shown in Figure 24, are a series of indicating devices such as light bulbs 207, one bulb being connected in a circuit 96, 97 with the switch 95 of each machine so that as each machine completes its operation the corresponding light bulb will either light or go out whereby the operator can be advised of the completion of the operation of all of the machines. The air tank 205 is preferably located centrally 95 of the table B as shown in Figure 1.

Describing the control for the various machines, as each machine completes its respective operation the corresponding light bulb 207 will be energized or de-energized as the case may be. Thus, the operator can watch these bulbs and after all of the machines have completed their operations, the table is ready 100 for an indexing movement. At this time the tools of each of the machines have performed their operations and have been withdrawn from the work by reason of the cams 110 and 105 110 115 120 125 130 135 140 145 150 155 160 165 causes compressed air to be supplied to the cylinder 49 for moving the carriage C as shown in Figure 6 for rotating or indexing the table B a distance corresponding to the notches 35 or stations D. After this indexing movement of the table, the operator then moves the disk 193 in the reverse direction or counterclockwise as shown in Figure 5, to rotate the valve controlling member 197 in the opposite direction for supplying compressed air to the opposite end of the cylinder 49 whereby the carriage C is restored to its initial position ready for the next indexing movement. Further movement of the disc 193 causes a reverse rotary movement of the valve controlling member 196 whereby compressed air is admitted below the piston 30 for restoring the locking member 24 into locking engagement with the table B. Still further rotation of the disc 193 causes the finger 194 to engage the switch control 199 whereby each of the electro-magnets 92 of the machines is de-energized. At this time the circuits 96, 97 are broken and the springs 91 of each machine cause the downward movement of the arms 89 to actuate the clutches 82 setting in motion each of the machine units. These units then perform automatically and simultaneously their respective operations and return automatically to their inoperative positions ready for the next indexing movement of the table.

I have also provided a novel oiling system and apparatus for supplying machine and cutting oil to the bearings and other parts of the machine which require oiling and also for supplying cutting oil to the tools during their operations. To this end I have provided a series of supply tanks 208, 209 and 210 which store machine oil, cutting oil and cutting compound respectively. The oil is supplied to these tanks by the supply pipes 211, 212 and 213. The oil is conducted from the tanks 208, 209 and 210 by the pipes or conduits 214, 215 and 216 respectively which preferably extend radially from the respective supply tanks to a point above the table where these pipes are arranged horizontally adjacent each other so as to extend circumferentially above the table B as shown in Figure 7. From these conduits the oil may be led at the various points above the machines and work to supply the same to the cutting tools and also to the moving parts of the machine. Thus, as shown in Figure 7, the oil from the machine oil supply pipe 214 may be conducted through the branch pipe 214' for supplying machine oil to the cup 217. Any number of these cups 50 may be provided for each machine conveniently located with respect to the various parts to be oiled. For example, the oil from the cup 217 may be conducted through the branches 218 to oil the various parts of the machine, as for example, the bearings 77,

shown for purpose of illustration in Figure 7. It should be understood that any number of the branch pipes 214' may be provided throughout the length of the pipe 214 to completely oil the machines and for supplying a constant flow of oil to the machine parts. In Figure 7, I have also shown an oil cup 219 with a sight feed 220, the oil being supplied to this cup through the branch conduit 221 which may be a further branch of the pipe 214'. If desired valves 222 may be provided for regulating the flow of oil from the various branch pipes to the machine parts. 223 is a branch pipe for conducting the machine cutting oil from the supply pipe 215 to a point 224 conveniently located above the tool 142 for supplying cutting oil to the tool during the operation of the same. 225 represents a valve controlling the flow of oil in the pipe 223. 226 is a support or guide for the lower end of the pipe 223 and this support may be carried by any convenient portion of the machine such as the jig 143. A pipe similar to pipe 223 may be provided for conducting cutting compound from conduit 216 to desired points. The air supply pipe 206 is also preferably arranged adjacent the oil supply pipes 214, 215, and 216 as shown in Figure 7. It is understood that suitable conduits are branched from this air pipe for supplying the air to the cylinders 31 and 49. For convenience I also prefer to group the various wires of the circuits indicated at 96 and 97 leading to the switch points 95 at a point adjacent the oil supply pipes and as shown in Figure 7, I may arrange all of these wires in the form of a single cable 227.

I have also provided means for catching the excess oil which drips from the tools and the various machines and returning this excess oil to the tank 210 for distribution through the pipe 216 for using the same as a cutting oil, for other convenient purposes. To this end I have provided a foundation member or supporting base 228 for the machine as shown in Figures 25 and 26. This foundation is adapted to support the outer series of machine units around the surface indicated at 229, while the inner series of machine units are supported around the surfaces indicated at 230. For catching the dripping oil and for conducting the same to a common point I have provided a plurality of radial lubricant gutters or conduits 231 which may connect at suitable points with the circumferential gutter 232. These radial conduits 231 preferably extend to a common compound well 233 where the excess lubricant from all of the machines and tools is accumulated. The lubricant from this well is adapted to be conducted through the supply pipe 213 to the cutting compound reservoir 210.

While it is believed from the foregoing description, the nature and advantage of my invention will be readily understood, I desire to have it understood that I do not limit myself to what is herein shown and described and that such changes may be resorted to when desired as fall within the scope of the claims.

What I claim as my invention is:—

10 1. A device for working metal comprising a work holder movable in a predetermined path, means for securing a plurality of pieces of work on said holder, a plurality of machines, means for indexing the work holder to move the said pieces of work to successive positions for being operated on by said machines, means for holding the work holder relatively stationary for a predetermined length of time at the points of indexing, said 15 machines being adapted to operate upon the work during the said stationary movements of the work holder, means for rendering each machine inoperative upon completion of its operation, and means actuatable upon completion 20 of the operation of each machine for indicating the inoperative state of the respective machines.

2. A device for working metal comprising a rotatable ring-shaped work table, means for indexing the table throughout its rotation, means for successively moving the table between the successive points of indexing, means for securing a plurality of pieces of work to the table, a plurality of machines positioned 35 within and without said ring-shaped table for successive operations on said pieces of work, means for rendering each machine inoperative upon completion of its operation, and common means for simultaneously starting each machine upon its operation following an indexing movement of its work holder.

3. A device for working metal comprising a work holder movable in a predetermined path, means for securing a plurality of pieces 45 of work on said holder, a plurality of machines, means for indexing the work holder to move the said pieces of work to successive positions for being operated on by said machines, each of said machines being provided 50 with a tool for operating on said pieces of work, means for simultaneously feeding said tools toward the work for operating on the pieces of work respectively, and means for automatically returning the tools to their initial 55 positions upon completion of the respective operations, said two last mentioned means being operable independently of said work holder.

60 4. A device for working metal comprising a work holder movable in a predetermined path, means for securing a plurality of pieces of work on said holder, a plurality of machines, means for indexing the work holder 65 to move the said pieces of work to successive

positions for being operated on successively by said machines, a source of lubricant, means for distributing the lubricant from said source to the said machines, a base supporting the machines, said base being provided with 70 means for conducting the surplus lubricant from the machines, a well for catching the surplus lubricant, and means for conducting the surplus oil to a supply tank.

5. A metal working machine comprising a 75 movable work holder, means for clamping the work to the work holder, means for indexing the work holder, said last named means comprising a locking element movable into engagement with the work holder for holding the same stationary between periods of indexing, power operated means controlling the movement of said locking element, and power operated means for moving the work holder to index the same, said power 80 operated means being operable independently of the means for actuating said work holder.

6. A metal working machine comprising a 85 movable work holder, means for clamping the work to the work holder, means for indexing 90 the work holder, said last named means comprising a locking element movable into engagement with the work holder for holding the same stationary between periods of indexing, power operated means controlling the movement of said locking element, power operated means for moving the work holder to index the same, and a common control for both said power means, operable independently of the control means for said work holder. 100

7. A device for working metal comprising an annular work table having an annular V-shaped rib on the underside thereof, a supporting member for said table having an annular groove registering with said rib, a plurality of anti-friction rolls mounted in said groove, said rolls having an annular V-shaped surface, adapted to cooperate with said rib for rotatably supporting said work table, means for securing a plurality of pieces of work on said table, a plurality of individual machines spaced around and adjacent to said work table, and means for indexing said work table to move said pieces of work to successive positions for being operated on by said machines. 110

8. A device for working metal comprising an annular work table having an annular V-shaped rib on the underside thereof, a supporting member for said table having an annular groove registering with said rib, a plurality of anti-friction rolls vertically adjustably mounted in said groove, said rolls having V-shaped peripheral surfaces adapted to cooperate with said rib for rotatably supporting said work table, means for securing a plurality of pieces of work on said table, a plurality of individual machines spaced around and adjacent to said work table, and means for indexing said work table to move said 120 125 130

pieces of work to successive positions for being operated on by said machines.

9. A device for working metal comprising a work holder movable in a predetermined path, means for securing a plurality of pieces of work on said holder, a machine mounted adjacent to said work holder, means for indexing said work holder to move said pieces of work to be successively operated on by said machine, a source of power for said machine, a clutch between said source of power and said machine for rendering the latter inoperative, a bell crank having an arm engageable with said clutch, yieldable means for holding said clutch normally engaged, a rotatable cam engageable with said bell crank for releasing said clutch, and means engageable with said bell crank for holding said clutch released against the tension of said yieldable means.

10. A device for working metal comprising a work holder movable in a predetermined path, means for securing a plurality of pieces of work on said holder, a plurality of individual machines mounted adjacent to the path of said work holder, each of said machines having a source of power, a clutch between said source of power and said machine for rendering the latter inoperative, a bell crank having an arm engageable with said clutch, yieldable means for holding said clutch normally engaged, a rotatable cam engageable with said bell crank for releasing said clutch, an electro-magnet adapted to engage said bell crank when the clutch has been released by the action of the cam, said magnet being adapted to hold the clutch-actuating bell crank in released arrangement of the clutch against the tension of the yieldable means, and means for simultaneously engaging the clutches of the machines.

11. A device for working metal comprising a work holder movable in a predetermined path, means for securing a plurality of pieces of work on said holder, a plurality of individual machines mounted adjacent to said holder, each of said machines having a source of power, a clutch between said source of power and machine for rendering the latter inoperative, a bell crank having an arm engageable with said clutch for actuating the same, yieldable means engageable with said bell crank for urging said clutch into engaged arrangement, a rotatable cam engageable with an arm of said bell crank for raising said arm to release said clutch, an electro-magnet for engaging said cam actuated arm when in raised position to hold the clutch in released arrangement against the tension of said yieldable means, and means comprising a switch for deenergizing said magnets of the plurality of machines simultaneously, whereby the clutches are re-65 turned to engaged arrangement.

12. A device for working metal comprising a work holder movable in a predetermined path, means for securing a plurality of pieces of work on said holder, plurality of individual machines mounted in spaced relation adjacent to said work holder, means for indexing the work holder to move said pieces of work to successive positions for being operated on by said machines, means for locking said work holder in said successive positions, means for causing said machines to become operative simultaneously, and a common control member for said indexing means, locking means, and controlling means including a valve adapted in one position to unlock the work carrier and in another position to lock the work holder, a valve adapted in one position to index the work holder and in another position to return the indexing mechanism, a contact member for causing the machines to become operative, and a rotatable disc having an operating handle, said disc carrying a member engageable with said valves by rotation of the disc, and a member carried by said disc engageable with said machine operating contact upon completion of the indexing and locking operations.

13. A device for working metal comprising a rotatable work table, a plurality of machines positioned adjacent said table for successive operation upon the work carried by said table, a source of lubricant, means for distributing the lubricant from said source to said machines, a circular base supporting the machines, said base being provided with a circumferential gutter for catching surplus lubricant, a well positioned centrally of said base, a plurality of radial conduits leading from said gutter to said well, a tank containing a cutting compound and means for conducting the lubricant in said well to the tank aforesaid.

14. A metal working machine comprising a rotatable work table provided at spaced circumferential points with recessed portions, means for indexing the table throughout its rotation including a segmental locking element adapted to successively engage said recessed portions, a base upon which said locking element is pivotally mounted, and fluid actuated means carried by said base for moving said locking element into and out of engagement with said recesses.

15. A metal working machine comprising a rotatable work table provided at spaced circumferential points with recessed portions, means for indexing the table throughout its rotation including a supporting base positioned exterior of said table adjacent the periphery thereof, a segmental locking element pivotally mounted upon said base and adapted to successively engage the recessed portions of said work table, an arm integral with said locking element and a fluid actuated pis-130

ton carried by said base and pivotally connected to said arm.

16. A device for working metal comprising a work holder movable in a predetermined path, means for securing a plurality of pieces of work on said holder, a machine mounted adjacent to said work holder, means for indexing said work holder to move said pieces of work to be successively operated on by said machine, a source of power for said machine, a clutch between said source of power and said machine for rendering the latter inoperative, means for disengaging said clutch, means engageable with the aforesaid means for retaining the clutch in released position, and contacts carried by the two last mentioned means respectively and adapted to close an electric circuit when the clutch is in released position for indicating the inoperative state of said machine.

17. A device for working metal comprising a work holder movable in a predetermined path, means for securing a plurality of pieces of work on said holder, a machine mounted adjacent to said work holder, means for indexing said work holder to move said pieces of work to be successively operated on by said machine, a source of power for said machine, a clutch between said source of power and said machine for rendering the latter inoperative, means for disengaging said clutch, means engageable with the aforesaid means for retaining the clutch in released position, and means operable when the clutch is in released position and controlled by the two last mentioned means for indicating the inoperative state of said machine.

18. A device for working metal comprising a work holder movable in a predetermined path, means for securing a plurality of pieces of work on said holder, a plurality of individual machines mounted adjacent to the path of said work holder, each of said machines having a source of power, a clutch between said source of power and said machine for rendering the latter inoperative, a bell crank having an arm engageable with said clutch, yieldable means for holding said clutch normally engaged, a rotatable cam engageable with said bell crank for releasing said clutch, an electro-magnet adapted to engage said bell crank when the clutch has been released by the action of the cam, a contact carried by said magnet, a second contact carried by said bell crank arm and adapted to engage the other contact for closing an electric circuit to indicate the inoperative state of said machine, and means for simultaneously engaging the clutches of the machines.

19. A device for working metal including a rotatable work table provided at spaced points with lugs, means for indexing the table throughout its rotation, means for successively moving the table between the

successive points of indexing including a carriage slideable as a unit along the line of travel of said table and provided with an arm adapted to successively engage the lugs on said work table, and power operated means for controlling the movement of said carriage.

20. A device for working metal including a rotatable table provided at spaced points with depending lugs, each lug being provided with an inclined face and a shoulder, means for indexing the table throughout its rotation, means for successively moving the table between the successive points of indexing including a carriage provided with an arm, and power operated means for reciprocating said carriage whereby said arm will successively engage the shoulder portion of each of said lugs and actuate said table during the forward movement of the carriage, said arm being adapted to slide over the inclined face of the next succeeding lug during the return movement of said carriage.

21. A device for working metal including a rotatable work table provided at spaced points along its bottom with depending lugs, means for indexing the table throughout its rotation, means for successively moving the table between the successive points of indexing including a carriage slideable as a unit below the table and provided with an upwardly extending arm engageable with said lugs, and power operated means for controlling the movement of said carriage.

22. A device for working metal including a rotatable table provided at spaced points with depending lugs, each lug being provided with an inclined face and a shoulder, means for indexing the table throughout its rotation, means for successively moving the table between the successive points of indexing including a two part carriage, links connecting said carriage parts, an arm carried by one of said parts and engageable with said lugs, and power operated means for reciprocating said carriage whereby said arm will successively engage the shoulder portion of each of said lugs and actuate said table during the forward movement of the carriage, said arm being adapted to slide over the inclined face of the next succeeding lug during the return movement of said carriage.

23. A device for working metal comprising a work holder movable in a predetermined path, means for securing a plurality of pieces of work on said holder, a plurality of machines, means for indexing the work holder to move the said pieces of work to successive positions for being operated on by said machines, means for holding the work holder relatively stationary for a predetermined length of time at the points of indexing, said machines being adapted to operate upon the work during the said stationary movements of the work holder, means for rendering each machine inoperative upon completion of its

operation, an indicating board, electric lamps on said board equal to the number of machines, and means actuatable upon completion of the operation of each machine for closing its respective lamp circuit to indicate the inoperative state of the machine.

5 In testimony whereof I affix my signature.
CHAUNCEY A. CORNELL.
